UNITED STATES PATENT OFFICE.

LOUIS STANKO, OF DENBO, PENNSYLVANIA.

AUTOMATIC RAILROAD SWITCH.

Application filed September 3, 1927. Serial No. 217,371.

This invention relates to automatic switching mechanism and has for one of its objects the provision of an automatic switch adapted to be operated by a projecting member of a locomotive as the latter approaches the switch.

Another object of my invention is the provision of an automatic switch adapted to be operated automatically and to be operated manually from a point at a distance from the switch.

A further object of my invention is the provision of signaling mechanism for informing an engineer when the switch has been manually manipulated.

A still further object of my invention is the provision of an adjusting mechanism for setting the manual operating member to respond to a predetermined movement.

20 Referring particularly to the drawing:

Fig. 1 is a side elevational view of a track and engine embodying my improved automatic switching apparatus.

Fig. 2 is a plan view of a track embodying 25 my invention.

Fig. 3 is a side elevational view of the releasing apparatus of my invention.

Fig. 4 is a sectional view taken on the line 4-4 of Fig. 2.

30 Fig. 5 is a sectional view taken on the line 5-5 of Fig. 2.

Fig. 6 is a detailed view of the manual operating mechanism of my improved automatic switching apparatus.

35 Referring particularly to Fig. 1 of the drawing, the numeral 10 designates a rod slidably mounted on an engine and operatively connected with an angular lever 11 and a rod 12, and with an operating lever 13 pivotally mounted in the cab of the engine. It should be understood that manipulation 40 of the operating lever will cause the slidably mounted rod 10 to be projected downwardly for a purpose hereinafter described.

45 The switch mechanism shown in Fig. 2 is particularly adapted to be employed in controlling the passage of a locomotive and train from the main track of a railroad to a branch thereof. The rail 14 is of the usual 50 construction and is extended through and past the branch while the rail 15 is curved away from the main line of the railroad, the rail 15 being made integral with the rail 15' of the branch line. A rail section 55 16, comprising a pivotally mounted rail section 17 is disposed forwardly substantially

parallel to the through rail 14 and is formed integral with a rail section 18 of the branch line which comprises a pivotally mounted, diagonally disposed rail section 19 having 60 a tapered end 20 adapted to be disposed adjacent the sides of the through rail 14. The pivotally mounted section 17 of the rail 16 is also provided with a beveled or tapered end portion 21 which is adapted to be disposed adjacent the side of the curved portion of the rail 15.

The free ends of the pivotally mounted rail sections 17 and 19 are mounted on a cross-member 22 which is disposed below 70 the rails and which is slidably mounted on a horizontal base 23 also disposed below said rails. This cross-member is adapted to be moved transversely of the track for the purpose of positioning the beveled end 20 of the rail section 19 adjacent the through track 14 when it is desired to cause the locomotive to travel off of the main track onto the branch line and to move the rail end 21 of the pivotally mounted rail section 17 adjacent the curved portion of the rail 15 for causing the locomotive to continue on the main line. It should be understood that the two pivotally mounted rail sections 17 and 19 are moved in unison with each other 80 by the cross-member 22 so that when one rail section is placed in contact with its adjacent rail the other pivotally mounted rail section is moved out of engagement with its adjacent rail.

90 The mechanism disclosed in detail in Figs. 2, 3, 4 and 5, is for the purpose of automatically causing the cross-member 22 to be moved selectively in one or the other direction by the approach of a locomotive. Triggers 24 are pivotally mounted on brackets 26 and 27, respectively, which are secured to the opposite end portions of a tie 28 located on the main line in advance of the branch line. These triggers are pivotally connected 95 with the extremities of the rods 29 and 30 which are disposed parallel to and outside of the rails of the track. The rearward ends of the rods 29 and 30 are pivotally connected with arms of angular levers 31 and 32, respectively, rotatively mounted on the base 23. The rod 30 is pivoted directly to the angular lever 32, and a spring 33 is disposed between the end of the rod 29 and the angular lever 31. A spring 34 attached 100 to the end of the arm 31' of the lever 31 resists the action of the spring 34 and when

the tension in the spring 33 is increased by forward movement of the rod 29 the angular lever 31 is rotated in a clockwise direction. The arm 31' of the angular lever 31 is attached to the end of the cross-member 22 and is adapted to move the latter and the pivotally mounted rail sections in the direction of the through rail 14 for the purpose of causing the locomotive to be guided onto the 10 branch line.

A rocker 35 is mounted on the cross-member 22, as shown in Fig. 5 and is provided with a catch 36 which is adapted to engage the edge of a pivotally mounted lever 37 for 15 holding the cross-member 22 after it has been moved in the direction of the rail 14 by the angular lever 31. The rocker 35 is secured to the cross-member 22 by a bolt 38 which is provided with a nut 39 for clamping 20 the rocker to the cross-member. A second bolt 40 is screwthreaded in the cross-member 22 and extends through a slot in the end of the rocker for guiding and holding the same in position during rocking 25 movements thereof.

The lever 37 is pivotally mounted on a block 41 secured to one of the ties and is adapted to be rotated in a substantially horizontal plane, said lever being guided by a 30 bracket 42. A spring 43 is attached at one end to an extremity of the lever 37 and at its other end to a tie as shown in Fig. 2. The spring 43 tends to rotate the long arm of the lever 37 in a clockwise direction for retaining 35 the beveled end 45 of the short arm thereof in contact with the catch 36 of the rocker 35.

The angle lever 32 is connected by a rod 46 and an arm 47 with a pivotally mounted 40 shaft 48 journaled at its ends in brackets 49 and 50 mounted on the base 23. A resilient member 51 is rigidly attached at its lower end to the shaft 48 and is adapted to rotate in unison therewith. The upper end 45 of the resilient member 51 is positioned to engage the extremity of the rocker 35 for pressing the latter downwardly against the action of the spring 52 for disengaging the catch 36 from the vertical portion 44 of the 50 lever 37. In Fig. 5 dot dash lines 36' simulating the position of catch 36 engaging the portion 44 are shown. Anticlockwise rotation of member 51 about 48 as a pivot will 55 force catch 36 downwards for freeing purposes. Dot dash lines 36' in Fig. 4 illustrate this condition. Rotation of the resilient member 51 is effected through the shaft 48, arm 47, rod 46, angle lever 32, and the rod 30 when an engine passes over the trigger 60 25 causing the latter to be pressed downwardly by engagement of the slide rod 10 mounted on the engine with said trigger. When the rod 10 has passed over the trigger 25 the above-mentioned mechanism is restored to its starting position by the action 65

of the spring 55 connected at one end to the lever 32 and secured at its other end to the base 23.

As shown in Fig. 5, a pin 56 is mounted on the bottom of the pivoted rail section 19, 70 and is disposed in a recess 57 in the cross-member 22. A spring 58 is disposed between the side member of the rail section 19 and a projection 59 on the cross-member 22. The pin 56 engages the end of the slot 75 57 in the cross-member 22 and holds the rail section 19 from further approach to the through rail 14, it being understood that the rail section 19 is resiliently pressed against the rail 14 by the spring 58 when the cross-member is moved in the direction of the through rail.

When the catch 36 is released the spring 34 retracts the cross-member 22 and causes the angular lever 31 to be rotated anti-clockwise resulting in a rearward movement of the rod 29 and resetting of the trigger 24.

It should be understood that the locomotive disclosed in Fig. 1 is provided with a right hand and a left hand actuating means such as the bar 10, and that these actuating members may be selectively positioned to engage either one of the triggers 24 and 25. When it is desired to have the locomotive continue in the direction of the main line the trigger 25 is pressed downwardly to release the catch mechanism 36 of the rocker 35 for permitting the cross-member to move the pivotally mounted rail sections 17 and 19 to the position shown in Fig. 2. If, however, the rails are already set in this position depression of the trigger 25 will not change their position. When it is desired to cause the locomotive to divert from the main line onto the branch line, the trigger 24 may be depressed for moving the cross-member and the rail section mounted thereon in the direction of the through rail 14. When the trigger 24 is pressed downwardly the cross-member is moved and retained in its adjusted position by the catch 36 and the lever 37. A switchman or attendant may manually shift the cross-member if it is desired to change the relation of the rails.

In order that the catch mechanism may be manually operated from a switchman's cabin, apparatus is provided for rotating the long end of the lever 37 in a clockwise direction for rotating the short end thereof out of contact with the catch 36 for releasing the cross-member 22 to permit movement of the rail sections 17 and 19. This apparatus is shown in Fig. 6 to comprise a rotatively mounted disc 60 having a slot 61 therein. A block 62 is slidably mounted in said slot and is adapted to be adjusted and held in a suitable position by the set screw 62' disposed in the disc 60. A connecting link 63 is pivoted at one end to the block 62 and at the other end to the lever 37. A cable 64 is at-

tached to the lower side of the disc 60 and is adapted to rotate the same for causing a rotation of the lever 37 to which the disc is connected. The free end of the cable 64 5 may be disposed in a shanty at a considerable distance from the switch if desired. A sign or signal 65 may be mounted on the disc 60 as shown in Fig. 6. This sign is preferable 10 for the purpose of informing the engineer of an approaching locomotive that his engine is to be guided past the branch line. The rear face of the sign is turned towards 15 the approaching engine as illustrated in full lines and the front side of the sign is directed to the engineer as illustrated in dotted lines, it being understood that the sign 65 rotates in unison with the disc 60.

Having thus fully described and shown 20 an embodiment of my invention, what is desired to be secured by Letters Patent of the United States, is:

1. Automatic switching apparatus for railways comprising a base plate mounted below the rails of a track, a slidable member 25 mounted longitudinally of said base plate, a rocker mounted on one end of said slidable member, a catch on said rocker, a lever having a beveled extremity mounted on a tie of said railway adapted to engage the catch 30 of said rocker for retaining said slidable member in a predetermined position, actuating mechanism comprising a trigger positioned in advance of said slidable member and operatively connected with said slidable member adapted to be pressed downwardly 35 when a locomotive passes thereover for moving said slidable member in the direction of said lever to cause the catch of the rocker thereon to engage the beveled end of said lever for retaining said slidable member in an adjusted position, and pivotally mounted rail sections operatively connected with said cross-member and adapted to be moved in unison therewith for guiding said locomotive 40 in a predetermined direction.

2. Automatic switching apparatus for railways comprising a base plate mounted below the rails of a track, a slidable member mounted longitudinally of said base plate, 50 a rocker mounted on one end of said slidable member, a catch on said rocker, a lever having a beveled extremity mounted on a tie of said railway adapted to engage the catch of said rocker for retaining said slidable member in a predetermined position, actuating mechanism comprising a trigger positioned in advance of said slidable member and operatively connected with said slidable member adapted to be pressed downwardly 55 when a locomotive passes thereover for moving said slidable member in the direction of said lever to cause the catch of the rocker thereon to engage the beveled end of said lever for retaining said slidable member in an adjusted position, pivotally mounted 60

rail sections operatively connected with said cross-member and adapted to be moved in unison therewith for guiding said locomotive in a predetermined direction, and releasing means comprising a pivotally 70 mounted trigger positioned in advance of said slidable member adapted to be pressed downwardly when a locomotive passes thereover for releasing said slidable member, and a spring connected at one end to 75 said slidable member and at the other end to said base plate for moving said slidable member to place said rail sections in a predetermined position for causing said locomotive to be guided by said rail sections in 80 a predetermined direction.

3. An automatic switch for railways comprising a pair of pivotally mounted rail sections, a base plate disposed below the free ends of said rail sections, a slidable member mounted longitudinally of said base plate, a lever pivotally mounted on a tie of said railway and extending over one end of said slidable member, a catch adjustably mounted on said slidable member adapted 90 to engage the adjacent end of said lever, a spring attached at one end to said lever and at the other end to a tie of said railway for urging said lever against said catch to hold said slidable member in an adjusted position, said rail sections being mounted at their free ends on said slidable member and adapted to be retained in position thereby, a shaft rotatively mounted on said base plate adjacent the catch of said slidable member, an arm secured to said shaft adapted to rotate therewith and to engage 95 said catch for urging the latter downwardly to release said slidable member, operating mechanism for rotating said shaft, and a spring attached to said slidable member for moving the latter and the rail sections mounted thereon when said catch is released.

4. An automatic switch for railways comprising a pair of pivotally mounted rail sections, a base plate disposed below the free ends of said rail sections, a slidable member mounted longitudinally of said base plate, a lever pivotally mounted on a tie of said railway and extending over one end of said slidable member, a catch adjustably mounted on said slidable member adapted to engage the adjacent end of said lever, a spring attached at one end to said lever and at the other end to a tie of said railway for urging said lever against said catch to hold said slidable member in an adjusted position, said rail sections being mounted at their free ends on said slidable member and adapted to be retained in position thereby, a shaft rotatively mounted on said base plate adjacent the catch of said slidable member, an arm secured to said shaft 115 adapted to rotate therewith and to engage 120 said catch for urging the latter downwardly to release said slidable member, operating mechanism for rotating said shaft, and a spring attached to said slidable member for moving the latter and the rail sections mounted thereon when said catch is released.

said catch for urging the latter downwardly to release said slidale member, operating mechanism for rotating said shaft, a spring attached to said slidale member for moving the latter and the rail sections mounted thereon when said catch is released, a disc rotatively mounted adjacent the outer end of said lever, having a slot therein, a block adjustably mounted in said slot, a link pivotally connected at one end to said block and

at the other end to said lever, and a cable attached to said disc for rotating the latter to move said lever against the action of the spring attached to the rear end thereof for disengaging the forward end of said lever from the catch of said slidale member. 15

In testimony whereof I have affixed my signature.

LOUIS STANKO.
